ELLIS W. BREWSTER, OF PLYMOUTH, MASSACHUSETTS, ASSIGNOR TO PLYMOUTH CORDAGE COMPANY, OF PLYMOUTH, MASSACHUSETTS, A CORPORATION OF MASSACHUSETTS.

MARKING DEVICE FOR ROPE.

Application filed July 29, 1926. Serial No. 135,677.

This invention relates to improvement in marking devices for rope.

The peculiar structure of a rope, so rough that it can not well receive print, and the incidents of the use of a rope, producing wear and abrasion on all sides so that it could not retain print, have made the question of how to mark a rope satisfactorily and permanently one of the problems of the ages. 10 At the same time the ease with which an unscrupulous salesman can misrepresent the material or the quality of any particular rope, and the efforts sometimes made, in the case of a poor rope, to impute the manufacture of it to other than its true maker, make it especially desirable that there should be some indisputable means by which the maker of a rope can permanently associate with his product some mark or intelligible sign which 20 can distinguish it from the product of other makers, or by which other specific information can be told regarding it.

The present invention provides a new device for this purpose which has the advantages that it does not require to extend continuously throughout the length of the rope; that it does not, except at intervals, introduce into the body of the rope any foreign material; and that in its preferred form it 30 may have the durability of metal, as contrasted with the frailty of paper or cotton in markers which have heretofore been proposed. Other advantages are that the maker of the rope, at his election, may either place 35 the marker at one location only in each length of rope, or may repeat the mark at such intervals as he desires along the length of the rope; and consequently may control very completely the amount of stock used in 40 markers.

These advantages, and the others which characterize the invention, are attained by embodying within the rope at one or more locations, but preferably at regular intervals, 45 interior tags which are physically secured to one of the rope elements, as to a yarn. These tags may be of soft metal or leather in thin sheet form, having sufficient inherent stiffness to be held in place on a yarn for a brief time during manufacture, until embedded, 50 coupled with sufficient inherent flexibility and freedom from resilience and brittleness to be capable of being bent around a rope yarn without fracture; and having such en-

during tenacity or cohesive strength as can 55 withstand all disintegrating forces which may be applied to it by relative movements among its adjacent rope elements throughout the life of the rope. Such a marker, made from thin sheet metal, or from a thin strip of leather, may be stamped in the form of a letter of the alphabet, or a trade mark symbol, as an anchor, or may be a plain sheet having distinctive perforations. Having 60 been secured temporarily on a rope yarn either before or while the rope is being made, such a tag becomes secured permanently in position when the said yarn has reached its 65 place in the assembly of yarns that make up a strand of the rope. As each tag is complete in itself there is no particular relation of proximity which need exist between it and any other tag in the same rope. The color 70 and the durability of a marker which is not subject to destructive corrosion, make the mark permanently distinguishable and readily discoverable upon the unlaying of the rope. Inasmuch as a rope yarn has a substantial diameter and a practically incompressible limit, the marking device which has 75 been wrapped around or among one or more yarns remains legible in aspect; and because of its flexible character it can be flattened when removed, for still greater legibility.

It is intended that the patent shall cover, 80 by suitable expression in the appended claims, whatever features of patentable novelty exist in the invention disclosed.

In the accompanying drawings:

Figure 1 represents the end of a rope, 85 showing the marking devices of the invention in place on a yarn of the rope;

Figure 2 shows such a marking device in its shape before insertion in the rope, to 90 which it may be restored after being found in and removed from the rope.

Figure 3 shows a tag slipped through the midst of a yarn to be temporarily held; and

Figure 4 shows a tag pinched upon a yarn 95 for the same purpose.

Referring to the drawings, 10 indicates a rope made of any sort of strands 11, each of which is made of yarns 12, each yarn in turn consisting of a group of individual fibres 13 of hemp. But this rope must be considered as typical of any rope, made of any material used for any purpose, as for example a ship's hawser, or a wire rope, or

the hemp centre of a wire rope, and whether the same be technically a yarn, twine or cord.

The invention makes use of a multiplicity of separate tabs, tags or markers, 14 preferably made of thin flexible sheet metal, such as copper, although leather and any of various other materials may be used. One specimen of such a tag is shown in Figure 2 in its plane form, as it looks before being introduced into the rope, or after being extracted therefrom and smoothed. In the particular case illustrated the mark on the tag has the form of a letter A, which may be assumed to be the initial of the maker of the rope, or it might be the trade mark of the maker, or might be a private signal indicating any particular variety of information, such as the quality or material of the rope, or the year when it was made, or the person on whose order it was made. Likewise other forms may be used, for example, a star or an anchor or a plane sheet, round or square, in which any word, date or mark is punched.

In constructing a rope embodying the invention, one of these tags is placed in the rope by securing it to one of the strands, preferably within the strand. This may be done as in Figure 3 by slipping it (14') edgewise through a yarn 12, between the fibres making up the small body of hemp which constitutes a yarn. If the metal be stiff enough it can be merely thrust in, having first been arranged at a proper angle of parallelism with the fibres in the yarn, and then friction will hold the tag temporarily in place. As the yarn moves forward into proximity to other yarns which are being assembled with it in the making of a strand, this tag, projecting from the yarn, is engaged by other yarns that are being assembled and is by them bent in among the yarns, in the midst of them all in form and position such that it occupies a minimum of space among and between them, being incidentally bent from its original plane shape into whatever shape thus happens. Or it may be that the tag (14'') is initially secured to the yarn by being bent around it, as in Figure 4. Or if leather is used it may be stuck to the yarn by a suitable adhesive.

In a strand having interior and exterior yarns, this tag would naturally and preferably be associated with one of the interior yarns. However, if the rope structure be such that every yarn at times comes to the surface, so that the particular place at which this marker is put may happen to be laid at the surface, it is possible to make sure that the mark will remain forever present in a rope and not destroyed by abrasion of the surface, by putting in additional markers, as frequently as may be desired, some of which may happen to be at the surface of the

rope but a considerable number of which will under the law of chances of distribution find lodgment in the rope at some protected interior position. Each tag thus introduced will remain permanently in the rope, will endure so long as the rope does and will be colorful and distinguishable whenever the rope is opened for examination, provided a proper quality of non-corrosive or otherwise durable metal is selected. Other materials than metal may be used, but metal is suggested because of its durability and its cheapness.

Preferably the metal chosen should be of such soft nature as to bend readily when compressed by other adjacent yarns, and so as not to injure any yarn by abrasion due to any small movement of yarn over its edges as it lies in the rope.

In the manufacture of such a rope the previously prepared tags are individually, at intervals, by a mechanism, set into one of the yarns which is moving on its way to enter a strand in the making of the rope. The tag may be thrust through the yarn between the fibres thereof, or it may be partly wrapped around that yarn by being folded and stuck or pinched on it. In either case in its first stage of attachment it is held thereon by friction or adhesion, but, as the yarn advances with this tag protruding from it, when the tag reaches the throat which the yarn is entering with all of the other yarns to make the strand, the proximity of the adjacent yarns will bend the protruding parts of the tag and will wrap them to a degree about the yarn; and they may find places between other yarns of the strand, and in any event the tag will be compressed into such thin quarters as to make practically no difference in the size of the rope at the place where the marker is.

It may be considered sufficient to place a single such tag in rope; or such tags may be introduced in multiple, at intervals throughout the length of the rope.

In the case of a rope used as a centre for a wire rope the tag might be put around the entire centre rope, as this will be covered by the wires before it is put to use.

I claim as my invention:

1. The combination, with a rope, of means associating information therewith comprising a thin, flexible tag, secured to a yarn within a strand of the rope and wholly located at and within the circumferential limits of said strand.

2. The combination, with a rope, of means associating information therewith comprising a flexible strip of distinctive aspect held on a yarn and embedded in a strand of the rope, and wholly located at and within the circumferential limits of said strand.

3. The combination, with a rope, of means associating information therewith compris-

ing a flexible plate passing through a yarn, tinctive aspect embodied within and protected by the body of the rope.

4. The combination, with a rope, of means associating information therewith comprising a flexible plate passing through a yarn between the fibres thereof and in part wrapped around the same yarn of the rope.

5. The combination, with a rope, of means associating information therewith comprising a thin, flexible metallic plate of dis-

15
associating information therewith comprising a multiplicity of tags set at intervals along the rope, within the rope and protected thereby, each tag being discontinuous with the other tags.

Signed at Plymouth, Massachusetts, this 20
22nd day of June, 1926.
